(57) **CLAIM**

The ornamental design for a handheld kitchen cutting appliance, as shown and described.

DESCRIPTION

FIG. 1 is a perspective view of the top and front of the handheld kitchen cutting appliance, showing our new design; FIG. 2 is a top plan view thereof;

FIG. 3 is a bottom plan view thereof;

FIG. 4 is an elevational view as seen from the top of FIG. 3; and,

FIG. 5 is a perspective view of the bottom and front thereof. The elevational views as seen from the left, right and bottom of FIG. 3 are identical to the elevational view shown in FIG. 4.
